PHILIP W. MOORE, OF EVANSTON, ILLINOIS, ASSIGNOR TO THE P. & M. COMPANY,
AT CHICAGO, ILLINOIS, A CORPORATION OF ILLINOIS.

RAIL-ANCHOR.

1,128,350.

Specification of Letters Patent.

Patented Feb. 16, 1915.

Original application filed December 15, 1913, Serial No. 806,773. Divided and this application filed October 5, 1914. Serial No. 865,088.

To all whom it may concern:

Be it known that I, Philip W. Moore, a citizen of the United States, residing at Evanston, in the county of Cook and State 5 of Illinois, have invented certain new and useful Improvements in Rail-Anchors, of which the following is a specification.

My invention relates to a rail anchor of the type disclosed in my co-pending application Serial No. 806,773, filed December 15, 10, 1913, and in my co-pending application Serial No. 865,087 filed October 5, 1914; the present application being a division of the first named application.

15 A rail anchor of this general type is made up of a yoke element, which is preferably, though not necessarily, an integral structure, and may be either rigid or slightly flexible as desired, and extends under the base of 20 the rail engaging the same at opposite sides, and of a wedge element or elements interposed between the yoke and the rail base, the function of which is to produce a wedging engagement of the yoke member with 25 the rail base, the intimacy of which is increased with a forward thrust of the rail, operating to bind the rail and hold it against a tie, or other stationary portion of the road-bed, to check its forward creeping. 30 tendency.

In application Serial No. 806,773, I have claimed specifically a rail anchor of this type in which a single wedge is interposed between the yoke and the bottom of the rail 35 base at one edge thereof and also as a modification the combination with the yoke of two separate wedges one arranged at each side of the rail.

40 In application Serial No. 865,087 I have shown and claimed a hollow wedge structure in which the wedge members diverge in the direction toward the tie and the yoke formed with surfaces correspondingly inclined so that a forward movement of the yoke under 45 impetus from the rail produces transverse crushing stresses against the hollow wedge member.

The present invention contemplates a rail anchor consisting of a yoke element and a 50 hollow wedge element so constructed and arranged that the forward thrust of the free element, for example, the yoke, tends to expand the wedge member, the resistance of the wedge member to this expanding strain

producing a positive engagement or hold of 55 the device on the rail whereby the tendency of the rail to creep is self-checked.

The invention has for its primary object to produce a rail anchor operating on this principle which will be strong, inexpensive 60 to manufacture and light in weight, which latter feature is a material consideration.

The invention is illustrated, in a preferred embodiment, in the accompanying drawings in which—

65 Figure 1 is a plan view of the anchor shown as applied to a railroad rail, Fig. 2, a vertical sectional view taken on line 2—2 of Fig. 1, the rail being shown in elevation, Fig. 3, a cross sectional view on line 3—3 of Fig. 1; Fig. 4, a view, in perspective, of the wedge element, and Fig. 5, a similar view of the yoke element with one of the hooks or jaws broken away.

70 Like characters of reference designate 75 like parts in the several figures of the drawings.

Referring to the drawings, A designates a railroad rail and B one of the cross ties on which the rail is laid. The anchor consists of a shoe or yoke C (Fig. 5) and a hollow wedge element D. One of these elements, the element D for example, is formed with a tie abutting flange E, the other being free to move toward the tie except so 80 far as it is prevented from said movement by the wedge engagement between the elements of the anchor and the rail.

85 The yoke C consists of a bar of metal formed with hooks or jaws F adapted to 90 bear against the upper surface of the base flange of the rail and with wedging surfaces G, G, which have a general slope, when the device is in position on the rail, from the points g on the back edge of the yoke 95 near the center downwardly toward the tie, and toward the edges of the rail base as indicated by the arrows in Fig. 5. The wedge element D is formed with two wedge members H, H, projecting divergently from the 100 tie abutting member E and preferably connected by a web J. The wedge members are formed on their inner adjacent sides with curved wedge faces K, K. The wedge members are thinnest at the web J and increase in thickness toward the tie abutting member E. The device is applied to a rail by placing the hollow element D under the 105

base flange of the rail against a tie B, and slipping the yoke over the edges of the rail base back of the wedge element and driving the same over the wedge members H, H, to ward the tie as far as it will go. This tends to produce transverse expansion of the hollow member D, that is, to force the wedges H, H away from each other. When the rail is thrust in the direction toward the tie by the impetus of a train, the engagement as between the parts of the anchor and between the anchor and the rail is intensified so that any tendency on the part of the rail to creep is self-checked.

15 While I have described my invention in a preferred embodiment, it will be understood that modifications in the form, construction and proportion of the parts might be made without departure from the invention.

20 I claim:

1. A rail anchor comprising a bar formed at opposite ends with hooks adapted to bear against the upper surfaces of the base flange of the rail on opposite sides thereof, and a tie abutting plate formed with a pair of wedge members which converge in the direction of said plate and are connected at their outer ends by a cross piece, said wedge members adapted to intervene between the bottom of the base flange and said bar, and the wedge members and bar being formed with coacting wedge faces which have an inclination with respect to the plane of the base of the rail both transversely and longitudinally thereof.

2. In a rail anchor, the combination with a one-piece yoke element adapted to extend around the base flange of the rail, of a wedge element, one of such elements being provided with a tie abutting member and the other adapted to stand out of contact with the tie, the wedge element being formed with a pair of wedge members spaced apart and converging in the direction toward the tie, and the yoke with wedge faces engaging the inner faces of the wedge members.

3. In a rail anchor, the combination with a one piece yoke element adapted to extend around the base flange of the rail, of a wedge element formed with a tie abutting member and with wedge members projecting divergently therefrom, said yoke member being formed with wedge faces engaging the inner faces of said wedge members.

4. In a rail anchor, the combination with a one piece yoke element adapted to extend around the base flange of the rail, of a wedge element formed with a tie abutting member, wedge members projecting divergently therefrom, and a connecting web, said yoke member being formed with wedge faces engaging the inner faces of said wedge members.

5. In a rail anchor, the combination with a yoke element which extends around the

base flange of the rail out of contact with the bottom thereof, of a hollow wedge element adapted to be interposed between the yoke element and the base of the rail, one of said elements being formed with a tie abutting member, and the other adapted to stand out of contact with the tie, said elements being provided with co-engaging wedge faces disposed to produce transverse stresses outwardly in opposite directions against said wedge members when the free member is moved in the direction of the tie.

6. In a rail anchor, the combination with a yoke element which extends around the base flange of the rail out of contact with the bottom thereof, of a hollow wedge element adapted to be interposed between the yoke element and the base of the rail, said wedge element being formed with a tie abutting member and with wedge members projecting therefrom, said elements being provided with co-engaging wedge faces disposed so as to produce transverse stresses outwardly in opposite directions against the wedge members.

7. In a rail anchor, the combination with a one piece yoke element adapted to extend around the base flange of the rail and a wedge element, one being provided with a tie abutting member and the other adapted to stand away from the tie; the wedge element comprising two wedge members spaced apart which are engaged by said yoke element so as to be subjected to stresses tending to spread said members apart.

8. In a rail anchor, the combination with a one piece yoke element adapted to extend around the base flange of the rail and a wedge element, one being provided with a tie abutting member and the other adapted to stand away from the tie; the wedge element comprising two wedge members spaced apart which lie generally lengthwise of the rail and are engaged by said yoke element so as to be subjected to stresses tending to spread said members apart.

9. A rail anchor comprising two elements having a wedging engagement one with the other, one of said elements consisting of an integral yoke extending around the base of the rail, one of them being provided with a tie abutting member and one of the elements being formed with two wedge members spaced apart which are subjected to stresses tending to spread the same by engagement with the other element.

10. In a rail anchor, the combination with a one piece yoke element adapted to extend around the base flange of the rail of a wedge element, one provided with a tie abutting member and the other adapted to stand away from the tie, said wedge element consisting of a hollow structure engaged by said yoke element so that stresses are produced tending to spread the same.

11. A rail anchor comprising two elements having wedging engagement one with the other, one of said elements consisting of an integral yoke extending around the base 5 of the rail, one of them being provided with a tie abutting member and one of said elements consisting of a hollow structure subjected to stresses tending to spread the same, by the wedging engagement between the 10 elements.
12. In a rail anchor, the combination with a one piece yoke element adapted to extend around the base flange of the rail of a wedge element, the wedge element being formed 15 with a tie abutting member and the yoke element adapted to stand away from the tie, said wedge element comprising two wedge members spaced apart and engaged by the yoke element so as to be subjected 20 to stresses tending to spread them.
13. A rail anchor comprising two elements having a wedging engagement one with the other, one of said elements consisting of an integral yoke extending around 25 the base of the rail, one of them being formed with a tie abutting member and with two wedge members spaced apart which are subjected, by the wedging action 30 between said elements, to stresses tending to spread them.
14. In a rail anchor, the combination with a yoke element adapted to extend around the base flange of the rail out of contact with the bottom thereof, of a wedging element formed with a tie abutting member 35 and with wedge members spaced apart and interposed between the yoke element and the bottom surface of the base flange of the rail,
- said elements being provided with co-engaging faces inclined from the horizontal 40 both longitudinally and transversely of the rail and disposed so that stresses are exerted against the wedge members tending to spread the same.
15. In a rail anchor, the combination with 45 a yoke element adapted to extend around the base flange of the rail out of contact with the bottom thereof, of a wedge element consisting of a hollow structure interposed between the yoke element and the bottom 50 surface of the base flange of the rail provided with a tie abutting member; said elements being provided with co-engaging faces inclined from the horizontal both longitudinally and transversely of the rail and 55 disposed so as to produce stresses tending to expand said hollow structure.
16. In a rail anchor, the combination with a yoke element adapted to extend under the base of a rail, engaging the rail on opposite 60 sides, and formed with inclined surfaces sloping from points on the back edge thereof adjacent the center downwardly toward the tie and the edges of the rail base, of a wedge element interposed between the yoke 65 and the rail base consisting of a tie abutting member, a pair of wedge members divergent from the tie abutting member and of decreasing thickness in the direction away from said member, and a web connecting 70 the ends of the wedge member remote from the tie abutting member.
